Primary Examiner—Alan P. Douglas*Assistant Examiner*—Angela J. Lee(74) *Attorney, Agent, or Firm*—Brinks Hofer Gilson & Lione(57) **CLAIM**

The ornamental design for a television receiver display layout, as shown and described.

DESCRIPTION

The sole FIGURE is a front view of a television receiver display layout of the present invention.

The broken line showing of the television receiver display, the vertical grid lines, and the various images in the left end column is included for the purpose of illustrating environmental structure and forms no part of the claimed design.
